SENDING UNIT FOR ELECTRIC SPEEDOMETERS

Artein W. Le Fevre, Chicago, Ill., assignor to
Stewart-Warner Corporation, Chicago, Ill., a
corporation of Virginia

Application October 2, 1936, Serial No. 103,748

14 Claims. (Cl. 201—48)

My invention pertains to sending units for electric speedometers, particularly adapted for automobiles in which the engine is located at the rear of the vehicle, and is an improvement on the electric speedometer disclosed in application, Serial No. 40,600, filed September 14, 1935.

An object of my invention is to provide an improved sending means for electric speedometers.

Another object is to provide a sending means for electric speedometers which more accurately translates the true speed of the vehicle at all times.

Another object of my invention is to provide a sending means for electric speedometers which is simple and which will be free from operating difficulties.

Another object is to provide a sending means for electric speedometers which is economical to manufacture.

Another object is to provide a sending means for electric speedometers in which the current-varying means is less affected by vehicle vibration.

Other objects and advantages will become apparent as the description proceeds.

In the drawings,

Figure 1 is a sectional view of a sending unit for electric speedometers embodying my invention, and shows this sending unit connected in an electrical circuit including speed and mileage-indicating means, the circuit and indicating means being diagrammatically shown.

Figure 2 is a transverse sectional view of the sending unit and is taken on the line 2—2 of Figure 1;

Figure 3 is another transverse sectional view of the sending unit and is taken on the line 3—3 of Figure 1;

Figure 4 is a partial sectional view showing a detail and is taken on the line 4—4 of Figure 2;

Figure 5 is a longitudinal section of an improved form of my invention;

Figure 6 is a side elevation on a reduced scale of the form of my invention shown in Figure 5;

Figure 7 is a transverse section taken on the line 7—7 of Figure 6;

Figure 8 is an end view looking in the direction of the arrow 8 of Figure 6;

Figure 9 is a transverse section taken on the line 9—9 of Figure 6; and

Figure 10 is a view showing the switch mechanism and is a section taken on the line 10—10 of Figure 9.

In Figures 1 to 4 of the drawings I have shown my improved sending unit for electric speed-

ometers as comprising a casting 10 of iron or other suitable magnetic material. This casting 10 is attached as by means of threads 12 to the part 14 of a transmission housing or other suitable stationary part of an automobile or other vehicle.

The casting 10 includes bearing sleeves 16 and 18 carrying a magnet shaft 20 which forms a separable connection 22 with a driving shaft 24 mounted in the part 14. The shaft 24 may be connected to or a part of the vehicle transmission or may be any other rotating part of the vehicle which rotates in a constant, predetermined speed relationship to one or more of the vehicle wheels.

The magnet shaft 20 drives a cup-shaped magnet support 26 to which is attached a permanent magnet 28 bent into the form of an annulus but having its ends separated by a suitable gap which 20 may either be left open or which may be filled with non-magnetic material, as desired. Across the ends of the magnet is a bypass regulator 30 which is clamped between the bottom of the cup and a shoulder 32 in such manner that the bypass 30 may be manually swung about its axis relative to the magnet 28. It is to be understood that the magnet 28 may be further provided with any usual temperature compensator.

The adjacent cylindrical wall 34 of the casting 10 cooperates with the magnet 28 in setting up an intense magnetic field therebetween. In this field is located a speed cup 36 of aluminum or other suitable material. This speed cup 36 is mounted on a shaft 38 journaled in bearings 40 and 42.

The bearing 40 comprises a jewel 44 mounted in a socket formed in the thin central portion of an insulating block 46 formed of a phenol condensation product or other suitable material. 40 The jewel 44 is held in place by a thin plate 48 attached to the central portion of the block 46 by hollow rivets 50. It is to be noted that the design and arrangement of the bearing 40 are such that this bearing and its support insulate the shaft 38 from the casting 10.

The lower bearing 42 comprises a jewel 52 which holds the shaft 38 against lateral movement, and a second jewel 54 which resists the longitudinal thrust of the shaft 38.

50 The jewels 52 and 54 insulate the lower end of the shaft 38 from the combined bearing support and oil shield 56. This oil shield and bearing support is made of brass or other non-magnetic material and is secured in place by the set screw 58. The jewels 52 and 54 are clamped in a socket

formed in the support 56 by an annular plate 60 attached to the support 56 by rivets 62. From the foregoing description of the bearings 40 and 42, it will be seen that these bearings completely insulate the speed cup shaft 38 from the casting 10.

The speed cup 36 is attached to its supporting shaft 38 in such manner that the tendency of the speed cup 36 to rotate with the magnet 28 is transmitted to the shaft 38. This shaft also carries for rotation therewith contact finger 64 having a short flexible upper end 66 and a rigid lower end 68 firmly attached to the hub 70 for rotation with the shaft 38. This finger 64 is made of current-conducting material and forms an electrical connection between the shaft 38 and a point on the resistance 72 over which the contact finger 64 slides. The resistance 72 is arranged in the form of an incomplete circle and comprises a strip 74 of suitable insulating material about which is wound a nichrome or other high-resistance wire 76. The resistance 72 is located in an annular slot defining structure of C-shaped cross-section comprising the insulating blocks 46 and 78 which are preferably made of the same material. The blocks 46 and 78 are held in clamped relation about the resistance 72 by bolts 80 and 82 and nuts 84 and 86, respectively.

The bolt 80 forms one electrical terminal of the sending unit and is in electrical communication with the shaft 38 and contact finger 64 through resilient plate 88 which engages one end of the shaft 38 and which has the further function of pressing this shaft lightly against the bearing jewel 54 so that longitudinal movement of the shaft is prevented. The plate 88 is clamped between nuts 84 and 90. The extension of the outer end of the plate 88 into the vertical groove 92 formed in the insulating block 46 prevents pivotal movement of the plate 88 about the bolt 80.

The rotational movement of the speed cup 36 and its shaft 38 are resisted by a spiral spring 94 attached to the upper end of the shaft 38. The other end of this spiral spring is attached to a metal plate 96 clamped between the nut 84 and the adjacent surface of the block 46. The plate 96 has an opening 98 for receiving the cup-like upward central projection of the block 46, and the plate 96 can be pivoted about this projection for purposes of adjustment. To permit such pivotal adjustment, the plate 96 has an arcuate slot 100 for receiving the bolt 80, and by loosening the nut 84 the plate 96 may be pivoted about the axis of the shaft 38 to adjust the tension of the spiral spring 94, and thereafter the nut 84 is tightened to clamp the plate 96 in adjusted position.

I have provided means to limit the movement of the shaft 38 under the influence of the spiral spring 94, and such means determines the stationary position of the shaft 38 and associated contact finger 64. This means comprises a stop member 102 of insulating material and rigid with the hub 70. This stop member 102 has a projection for engaging the depending finger 104 of a metal annulus 106 supported on a shoulder 108 provided by the casting 10. A pin 110 prevents rotation of the annulus 106.

One end of the resistance wire 76 of the resistance 72 is connected by a very short lead 112 to a washer 114 mounted on the bolt 82 and clamped in place by nut 86. It will thus be seen that the bolt 82 forms another electrical terminal for the sending unit. The resistance 72

is also grounded to the frame of the automobile. The other end of the resistance wire 76 of this resistance is connected by a short lead 116 to a plate 118 adjustably located in a recess provided in the insulating block 46. The plate 118 has an arcuate slot 120 receiving the upper end of a stud 122, the plate being held in place by a nut 124 threadedly engaging the upper end of the stud 122. The lower end of the stud 122 passes through and is in electrical engagement with the annulus 106 whereby an electrical communication is established between the lead 116 and the casting 10. The casting 10 is directly or indirectly attached to and therefore grounded to the frame of the automobile or other vehicle and forms a ground for the resistance 72.

The foregoing arrangement permits ready adjustment of the position of the resistance 72 relative to the stop finger 104. The resistance 72 may be angularly shifted in the annular groove formed by the blocks 46 and 78, and this movement of the resistance 72 can be accommodated by pivoting the tongue of the terminal 114 about the terminal 82 and by shifting the relation of the arcuate slot 120 of the terminal 118 and by shifting the relation of the arcuate slot 120 of the terminal 118 relative to the stud 122.

The block 46 and attached parts are held against rotation and longitudinal displacement by a set screw 126. These parts are also held against longitudinal displacement by a metal ring 128. The upper end of the sending unit is closed by a cover comprising a disk 130 of insulating material and a metal cap 132. Screws 134 attach the cap 132, plate 130 and ring 128 to the upper end of the casting 10.

Terminals 80 and 82 project through suitable openings provided in the disk 130 and cap 132. Each terminal is surrounded by a stepped sleeve 136 of insulating material above which is a metal washer 138 and nut 140 for attaching an end of a wire to each terminal. It is to be noted that each terminal and its associated wire is separated from the metal cap 132 to prevent grounding of either connection therethrough.

I preferably provide the casting 10 with an opening which is shown as being closed by a plug 141. This opening is for permitting the insertion during the assembly operation of a clearance gauge between the collar 33 and the end of the bushing 18, while the lip 35 at the opposite end of shaft 20 is peened over the collar 37.

The magnet shaft 20 comprises a worm 142 for driving a cross shaft 144 mounted in bushings 146 and 148 carried in the lower part of the casting 10. This cross shaft has a worm 150 for driving a stub shaft 152 rotatable in bushings 154 and 156 also mounted in the lower portion of the casting 10. The chain of connections thus far described comprises a speed-reducing drive for a cam 158 formed on the end of the stub shaft 152.

This cam 158 constitutes a means for closing a switch 160 having a stationary contact 162 carried on an arm 164 attached to the head of a terminal 166 carried by an insulating cover 168 suitably attached to the casting 10 to close a pocket formed therein. The movable contact 170 is mounted on a resilient arm 172 attached to the casting 10 by a screw 174.

The tension of the resilient arm 172 is such that it tends to open the switch 160 and holds

the tail 176 in contact with the cam 158. This cam is formed by simply cutting off the end of the shaft 152 at an angle, as clearly shown in Figure 3 of the drawings. As this cam 158 rotates, the switch 160 opens and closes at periodic intervals, bearing a definite relation to the rotation of the driving shaft 24 and therefore bearing a definite relation to the distance traveled by the vehicle. It is to be understood that the switch-carrying arm 164 is made sufficiently resilient to yield slightly when the switch contacts 162 and 170 are engaged.

From the foregoing description of my improved sending unit for electric speedometers, it will be appreciated that I have invented a sending unit which is simple to manufacture, easy to assemble, and which may be adjusted conveniently for proper calibration. Particular attention is called to the fact that the main casting 10 provides the field plate for the magnet 28 and that the annular plate 106 is also made of iron or other magnetic material and constitutes a continuation of this field plate whereby maximum efficiency is achieved.

In order to facilitate assembly, I have so designed my improved sending unit that the insulating blocks 46 and 78, and all of the parts attached to or carried by these blocks, may be readily formed as a sub-assembly before insertion in the upper end of the casting 10. Furthermore, most of the relationships of this sub-assembly are independent of the rest of the mechanism, and those that are related to the rest of the mechanism, such as the relationship between the stop 104 and the spring 94 and resistance 72 can be readily adjusted after the sub-assembly has been placed in the casting 10.

Another feature of my invention lies in those design characteristics which prevent the operation of the sending unit from being affected by vehicle vibration. In this connection, I wish to call particular attention to the short length of the resilient part of the contact finger 64 and the rigid support for this resilient part, and also the firm and protective support provided for the resistance 72.

The short leads for the resistance 72 materially improve the sensitiveness and accuracy of the sending unit by reducing the amount of the non-variable resistance in the circuit of which this resistance 72 forms a part. The provision for accurate adjustment of the resistance relative to the contact finger 64 and its stop 104 also contribute to the accuracy of the instrument. The simplicity and ruggedness of the design of my sending unit materially contribute to the long life of the unit and the maintenance of accurate calibration throughout this long life.

In Figure 1 of the drawings I have diagrammatically illustrated the electrical circuit in which my sending unit is used and the indicating means connected with this circuit. In this Figure 1 I have shown a conventional automobile battery 180 which is grounded to the automobile frame at 182. The other side of the battery 180 is connected to the usual ignition switch 184 which controls the usual engine ignition system, not shown. In addition to controlling the engine ignition, this switch 184 also controls three balanced circuits A, B and C, which form part of the electric speedometer. The circuit A includes motor coils 186 and 188 and is grounded to the automobile frame at 190. The coils 186 and 188 act in opposite directions on a pivoted armature 191 which controls a pointer 75

192 moving over a scale for indicating the vehicle speed.

The second circuit B includes the resistance 72, one end of which is connected to the ignition switch 184 by way of terminal 82 and wire 194, and the other end of which is grounded through the casing of the sending unit, as best shown in Figure 4. The circuits A and B are in parallel, and the relative strengths of coils 186 and 188 in circuit A are controlled by movement of the contact finger 64 over the resistance 72 of circuit B. This contact finger 64 is connected through its supporting shaft 38, plate 88, terminal 80 and wire 196 with a point 198 of circuit A which is located intermediate the coils 186 and 188. Since the position of the contact finger 64 with respect to the resistance 72 is accurately determined at all times by the speed of the vehicle, the pointer 192 of the indicating 20 means accurately indicates vehicle speed.

The third circuit C includes an electromagnet 199 and switch 160 and is likewise grounded to the vehicle frame through the casting 10. The electromagnet 199 periodically attracts an armature 200 and thereby actuates a pawl 202 which engages a ratchet wheel 204 attached to the drum of a mileage indicator.

It will be understood that the speed and mileage indicators are preferably located on the instrument board of a vehicle in such position that they may be readily seen by the driver. Because of the balanced relationship between the circuits A, B and C and the design of these circuits and cooperating instrumentalities, the speed and mileage indicating means may be mounted in the same casing, if so desired.

In Figures 5 to 10 of the drawings, I have illustrated another form of my invention which is essentially the same as that shown in Figures 1 to 4, 40 but which represents several improvements thereover. Referring to Figure 5, I have shown the preferred form of my invention as having a combined field plate and housing 210 comprising a steel sleeve, to one end of which is diecast a base 212 which carries the magnet shaft 214 for rotating the magnet 216. The diecast base 212 has a threaded end 218 whereby the entire unit may be attached to a transmission part like the part 14 shown in Figure 1 of the drawings. 50 It is to be understood that the magnet shaft 214 is connected in driving relationship with a driving shaft like the shaft 24 of Figure 1 of the drawings, the magnet shaft 214 being provided with a rectangular opening 215 for this purpose.

As shown most clearly in Figures 6 and 7, the diecast base 212 is provided with a pair of laterally extending lugs 220 having openings 222 for receiving bolts or other attaching means whereby the entire unit may be secured to the frame or other part of an automobile. The lugs 220 may be used either separately or in combination with the threaded portion 218 to provide a more rigid support for the sending unit. In instances where the magnet shaft 214 is connected to a rotating part of an automobile by means of a flexible driving connection, the lugs 220 will form the sole support for the sending unit.

The substitution of the steel sleeve 210 and diecast base 212 for the unitary iron casting 10 of the embodiment of Figures 1 to 4 reduces the weight of the sending unit, and in this respect the form shown in Figure 5 is an improvement over that shown in Figure 1. Both the iron casting 10 of Figure 1 and the steel sleeve 210

and die casting 212 of Figure 5 are entirely satisfactory from an operating standpoint.

In the embodiment of Figure 5, the combined bearing support and oil shield 224 is attached to the die casting 212 by studs 226 which receive nuts 228 and metal washers 230. Resilient washers 232 of rubber or other suitable material are interposed between the metal washers 230 and the adjacent shoulder of the die casting 212. These resilient washers 232 form a seal which prevents leakage of water or foreign matter into the chamber containing the magnet 216, and these washers 232 have the further function of forming a cushion which prevents injury to the parts when the nuts 228 are tightened.

The form of my invention shown in Figure 5 also includes improved bearing means for the shaft 234 which carries the speed cup 236 and the pointer 238. The lower end of the shaft 234 is held against lateral displacement by a jewel 240 confined between plate 242 and flange 244 of the support 224. The lower end of the shaft 234 rests upon a jewel 246 carried in a movable holder 248 urged upwardly by a spring 250 resting upon the bottom of a cup 252 attached to the under side of the bearing support 224.

The spring 250 normally holds the holder 248 so that its upper end rests against the flange 244. Whenever the sending unit is subjected to a shock or jar which urges the shaft 234 downwardly against the bearing 246, the spring 250 yields slightly and absorbs the shock whereby damage to the parts is prevented and the life of the sending unit is materially prolonged. The amount of movement permitted the bearing 246 is so slight that the corresponding movement of the shaft 234 with its speed cup 236 and pointer 238 does not interfere with the operation of the instrument.

The upper end of the shaft 234 is held against lateral displacement by a jewel 254 located in a recess formed in the central portion of the insulator block 256 and held in place by a metal plate 258. A screw plug 260, adjustably mounted in finger 262, constitutes an adjustable end thrust bearing for the shaft 234.

The insulator block 256 is secured to the upper end of the steel sleeve 210 by screws 264 which pass through the upper end of the sleeve 210 and engage in an annular recess 266 formed in the lower end of the block 256. The insulator blocks 256 and 268 cooperate to provide a recess for receiving the resistance 270, as in the previous embodiment. It will be understood that these blocks 256 and 268 are preferably formed of a phenol condensation product or other suitable material.

Another feature of the embodiment shown in Figure 5 is the improved means for securing the cover to the sending unit. This cover 272 is attached to the unit by means of bolts 274 and 276, whose heads are molded into the block 268. The cover 272 has eyes 278 and 280 which surround bolts 274 and 276, respectively. The eye 278 is confined between nuts 282 and 284, and the eye 280 is confined between nuts 286 and 288. The open end of the cover simply slides over the adjacent end of the sleeve 210, and the arrangement is such that tightening of the nuts 284 and 288 to secure the cover firmly in place does not tend to pull the bolts 274 and 276 out of the insulator blocks 256 and 268.

The spring 290 for resisting rotation of the shaft 234 has one end attached at 292 to an adjustable plate 294, as in the previous embodiment.

The spring 290 with its supporting plate 294 and the finger 262, both serve to establish an electrical connection between the pointer 238 and the bolt 274 which forms one terminal of the sending unit. The end 293 of the resistance 270 is connected to a metal strip 294 carried on the bolt 276 which forms another electrical terminal of the sending unit. The other end of the resistance 270 is grounded through plate 296, 10 as in the previous embodiment. This plate 296, like the corresponding plate of the previous embodiment, is made of magnetic material and constitutes a continuation of the field plate, and this plate 296 also forms a stop for the shaft 15 234.

The embodiment of Figures 5 to 10 also includes an improved form of switch mechanism for controlling the odometer. As best shown in Figures 5, 9 and 10, the magnet shaft 214 drives 20 a cross shaft 300 which in turn drives a stub shaft 302 carrying a switch operating cam 304. This cam contacts and moves the resilient switch arm 306 carrying movable contact 308 which is adapted to cooperate with a stationary contact 310 mounted on a second switch arm 312 which may be slightly resilient, if desired.

The cam 304 is of the single lobe type and is designed to open and close a switch formed by the contacts 308 and 310 once for each revolution of the shaft 302, the cam being especially designed to give a substantially uniform movement to the finger 306 and to prevent sudden engagement or disengagement of the contacts 308 and 310.

35 The resilient finger 306 is grounded to the automobile frame by being directly attached to the die casting 212, as by means of screw 314. The switch arm 312 is connected to bolt 316 which is insulated from its supporting plate 318 by insulating disks 320, 322 and 324.

It is to be understood that the preferred form of my sending unit shown in Figures 5 to 10, inclusive, is intended to be connected into an electrical circuit in the manner indicated in Figure 1 in connection with the earlier form of my invention. It will further be understood that the mode of operation of the sending unit shown in Figures 5 to 10, inclusive, is the same as that of the sending unit shown in Figures 1 to 4.

50 While I have illustrated and described only two forms of my invention, it is to be understood that my invention may assume numerous forms and that the scope of my invention is therefore limited solely by the following claims.

55 I claim:

1. In a sending unit for electric speedometers, the combination of a magnet shaft, a magnet driven thereby, a speed cup associated with said magnet, a variable rheostat controlled by said speed cup, and a single casting enclosing said shaft, magnet, speed cup and rheostat, and forming a field plate for said magnet.

60 2. In a sending unit for electric speedometers of the class described, the combination of a casting, a shaft rotatably mounted therein, a magnet driven by said shaft, a speed cup rotatably supported in spaced relation to said magnet, said casting having a portion enclosing said magnet and speed cup and forming a field plate for said magnet, and means controlled by said speed cup.

65 3. In a sending unit of the class described, the combination of a casting having a base and cylindrical portions of two internal diameters, a shaft mounted in said base, a magnet driven by said shaft, a speed cup associated with said mag-

net, said magnet and speed cup being located in the cylindrical portion of smaller internal diameter, a resistance located in said portion of larger diameter, means controlled by said speed cup for varying said resistance, said portion of smaller internal diameter constituting a field plate for said magnet, and a plate separating said portions and constituting a continuation of said field plate.

4. In a sending unit for electric speedometers, the combination of a magnet, means for rotating said magnet, a speed cup associated with said magnet, a member forming a field plate for said magnet, a variable resistance controlled by said speed cup, and a second member forming a continuation of said field plate and a grounding connection for said resistance.

5. In a sending unit for electric speedometers, the combination of a shaft, a contact finger mounted thereon, a spring for moving said contact finger in one direction, means for moving said contact finger in the other direction, and a sub-assembly comprising a resistance for co-operation with said finger, means adjustably supporting said resistance, an adjustable terminal for each end of said resistance, an adjustable support for said spring, and a stop for said contact finger.

6. In a sending unit for electric speedometers, the combination of a magnet shaft, a magnet driven thereby, a speed cup associated with said magnet, a variable rheostat controlled by said speed cup, and a unitary structure enclosing said shaft, magnet, speed cup and rheostat and forming a field plate for said magnet.

7. In a sending unit for electric speedometers, the combination of a magnet shaft, a magnet driven thereby, a speed cup associated with said magnet, a variable rheostat controlled by said speed cup, and a unitary structure enclosing said shaft, magnet, speed cup and rheostat, said structure comprising a sleeve forming a field plate for said magnet and a base die cast to one end of said sleeve.

8. In a sending unit for electric speedometers, the combination of a magnet shaft, a magnet driven thereby, a speed cup associated with said magnet, a variable rheostat controlled by said speed cup, a steel sleeve forming a field plate for said magnet, and a base die cast to said sleeve, said base providing lugs for attaching said unit to a support.

9. In a device of the class described, the combination of a shaft, electromagnetic means for rotating said shaft, a thrust bearing for said shaft, and a resilient support for said bearing.

10. In an instrument of the class described, the combination of a shaft, electromagnetic means for rotating said shaft, a thrust bearing for one end of said shaft, a resilient support for said bearing, and an adjustable thrust bearing for the other end of said shaft.

11. In a sending unit for electric speedometers of the class described, the combination of a magnet, means for rotating said magnet, a speed cup associated with said magnet, a shaft supporting said speed cup, a jewel thrust bearing for one end of said shaft, a slideable metallic support for said bearing, a spring urging said support in one direction, means limiting movement of said bearing in the opposite direction, and bearing means for the other end of said shaft.

12. In a sending unit for electric speedometers, the combination of a magnet shaft, a magnet driven thereby, a speed cup associated with said magnet, a variable rheostat controlled by said speed cup, an enclosing structure, an insulator block carried by said structure, a bolt provided on said block, a cover slidably related to said structure, and a pair of nuts on said bolt engaging opposite sides of said cover and securing said cover to said structure.

13. In a sending unit for electric speedometers, the combination of a magnet shaft, a magnet driven thereby, a speed cup associated with said magnet, a second shaft supporting said cup, a bearing support for said second shaft, a base having an opening therethrough, a stud attached to said bearing support and passing through said opening, a nut secured to the end 35 of said stud, and a resilient washer interposed between said nut and said base and forming a seal and cushion therebetween.

14. In a sending unit for electric speedometers, the combination of a magnet, means for rotating said magnet, a speed cup associated with said magnet, a shaft fixed to and supporting said speed cup, a contact supported by said shaft, an enclosing structure for said magnet and speed cup forming part of the field plate 45 for said magnet, means enclosed by said structure supporting one end of said shaft, and a sub-assembly for completing the field plate and supporting the other end of said shaft, said sub-assembly including a pair of insulating blocks defining an inwardly facing annular channel, resistance means held in place between said blocks, an annular field plate for completing the field, and a terminal for said resistance means for securing the blocks and plate together.

ARDEN W. LE FEVRE.
